J. F. LARKIN

BALL AND SEAT

Filed March 22, 1924

UNITED STATES PATENT OFFICE.

JAMES F. LARKIN, OF LOS ANGELES, CALIFORNIA.

BALL AND SEAT.

Application filed March 22, 1924. Serial No. 701,161.

My invention relates to the art of pumping oil wells which also produce sulphur water and sand. In this art a pump barrel is usually secured to the tubing of the well 5 near the bottom thereof, a plunger being reciprocated in this pump barrel by means of sucker rods which pass upwardly through the tubing usually to a walking beam situated in the derrick. A standing valve is 10 provided closing the bottom of the pump barrel below the plunger and a working valve is also provided in the plunger.

It is a very difficult matter to provide valves which will remain tight in a well 15 which contains sand and sulphur water in addition to the oil. It is an object of my invention to provide such valves.

In the standard form of pump, it is common to provide a steel ball which seats on a 20 steel seat and various alloys of steel have been used for this purpose. I have found that such metal valves and seats deteriorate very rapidly where they are exposed to the action of sulphur water and sand. This deterioration I avoid by making the valve and seat of glass.

Further objects and advantages will be made evident hereinafter.

Referring to the drawing which is for 25 illustrative purposes only,

Fig. 1 is a side elevation, partly in section, of an oil well equipped with my invention.

Fig. 2 is a section on an enlarged scale, of one embodiment of valve made in accordance with my invention.

In the usual form of pumping equipment, shown in Fig. 1, there is provided a walking beam 11 operated by any suitable means, not shown. Secured to the walking beam 40 11 is the upper end of a string of sucker rods 12 which, in turn, are secured at their lower ends to a plunger 13, sliding in a pump barrel 14. The pump barrel 14 is carried on tubing 15 which extends up to and passes 45 through a casing head 16. A stuffing box 17 surrounds the upper end of the sucker rods 12. Closing the lower end of the pump barrel 14 is a standing valve not shown in the drawing and closing a central opening 50 through the plunger 13 is a working valve 19.

The valves are similar in construction and consist of a seat 20 and a ball 21. In pumping oil wells, which carry considerable sand

and some sulphur water, the deterioration of 55 the ball 21 and the seat 20 are very rapid due to mechanical and chemical action.

In the practice of my invention, I provide a ball 21 and a seat 20 which are formed 60 of glass. The ball 21 is preferably solid and is cast or formed of molten glass in approximately spherical form and of a diameter slightly larger than the finished ball. The ball is then ground accurately in spherical form to the desired dimension. The seat 65 20 is similarly formed from molten glass and an annular spheroidal surface 22 is ground thereon by rotating the ball 21 in contact therewith, a paste of abrasive being applied to the surface 22 to assist in this grinding. 70

The finished ball and seat form a tight contact along the surface 22. This contact, due to the affinity of water for ground glass, is peculiarly efficient in holding oil pressure, the small space between the ball and 75 seat having a capillary film of water therein which resists intrusion of oil therein. At the same time, this water film prevents actual contact of the surfaces, and greatly minimizes the wear.

The form of valve seat especially adaptable to use in oil well pumps consists of a cylindrical body 23 provided with an annular supporting flange 24 which seats upon a ledge 25 formed in the wall of the plunger 85 and is retained securely in place by the lower face of a cage 26, which is threaded into the plunger.

In addition to the very great advantage 90 of providing valve surfaces having an affinity for water, the glass has the additional advantage of being almost entirely chemically inert in both water, sulphur water, and oil. Where metal surfaces are used in such liquids, considerable chemical action takes place, perhaps due to local electrolysis and a rapid deterioration of the exposed surfaces. Glass is not affected chemically, either by the oil, the water, or by any substances commonly found in solution in said 95 water.

In addition to the above advantages, the glass valve and seat are peculiarly well adapted to resist the mechanical cutting action of silt or sand. Where metal valves are used, they are rapidly cut away by the sand or silt.

Valves constructed in accordance with my

invention have a very long life, even under conditions in which a metal valve and seat rapidly wear away.

I claim as my invention:

- 5 1. In a pump for use in oil wells containing water and carrying sand or other abrasive impurities, the combination of: a valve seat; and a valve seating thereon, said valve and seat being formed of a material having a greater capillary affinity for water than for oil, the contacting surfaces of said valve and seat being ground to roughen the surface thereof and thus increase this capillary affinity.
- 10 2. In a pump for use in oil wells containing water and carrying sand or other abrasive impurities, the combination of: a valve seat; and a valve seating thereon, said valve and seat being formed of glass which has a greater capillary affinity for water than for oil, the contacting surfaces of said valve and seat being ground to roughen the surface thereof and thus increase this capillary affinity.
- 15 3. In an oil well pump, the combination of: a seat of slightly roughened glass; and a ball closing the opening in said seat.
- 20 4. In an oil well pump, the combination of: a seat; and a ball of slightly roughened glass for closing the opening in said seat.
- 25 5. In an oil well pump, the combination of: a valve seat of slightly roughened glass and a ball valve of slightly roughened glass.
- 30 6. In a method of forming a glass valve seat in an oil well pump, the step comprising: grinding a glass seat by means of a ball, said grinding being done in such a manner as to provide said glass seat with a slightly roughened surface.
- 35 7. In a method of forming a glass valve seat in an oil well pump, the step comprising: grinding a glass valve seat by means of the glass ball which is to be used with said seat in such a manner as to provide

said glass valve seat and said glass ball 45 with slightly roughened surfaces.

8. In a plunger pump for use in oil wells containing water and carrying sand, or other abrasive impurities, the combination of: a valve seat consisting of a cylindrical body 50 and an annular flange extending therefrom; means for retaining said valve seat in position in the plunger of said pump; and a valve seating on said seat, said valve and said seat being formed of a material having a greater capillary affinity for water than for oil, the contacting surfaces of said valve and seat being ground to roughen the surfaces thereof and thus increase this capillary affinity.

9. In a plunger pump for use in oil wells containing water and carrying sand, or other abrasive impurities, the combination of: a valve seat consisting of a cylindrical body 65 and an annular flange extending therefrom; means for retaining said valve seat in position in the plunger of said pump; and a valve seating on said seat, said valve and said seat being formed of glass which has a greater capillary affinity for water than for oil, the contacting surfaces of said valve and seat being ground to roughen the surfaces thereof and thus increase this capillary affinity.

10. In an oil well plunger pump, the combination of: a valve seat formed of a cylindrical body provided with an annular flange adapted to be retained upon a ledge in the pump plunger, said cylindrical body and annular flange being formed of ground glass; 75 and a ball valve formed of ground glass 80 adapted to close the upper end of said cylindrical body.

In testimony whereof, I have hereunto set my hand at Los Angeles, California, this 15th day of March, 1924.

JAMES F. LARKIN.
